METHOD OF AND APPARATUS FOR RECOVERY AND UTILIZATION OF SULPHUR DIOXIDE IN SULPHITE PULP MANUFACTURE

Edward M. Frankel, Cedarhurst, Md., assignor to West Virginia Pulp and Paper Company, New York, N. Y., a corporation of New York

Application August 8, 1935, Serial No. 35,289
Renewed April 25, 1940

7 Claims. (Cl. 23—131)

My present invention relates to improvements in the recovery and utilization of sulphur dioxide and other values in sulphite pulp manufacture.

While the advantages of cooking with high concentrations of SO_2 , namely, better fiber penetration, shorter cooking time at lower temperatures, resulting in stronger pulp and higher yields, have been known, yet such advantages have been imperfectly realized in practice. It is accordingly a principal object of my invention to devise an improved recovery process and apparatus while providing for an easily controlled circulation of SO_2 through the digester and recovery system whereby the concentration of SO_2 in the digester may be kept at the highest value consistent with the temperature of cooking selected. A further object is to provide such a process and apparatus which will be characterized by simplicity of construction and reliability 20 of operation.

My invention is predicated essentially upon an improved handling of the digester relief. In the operation of sulphite pulp digesters, wood chips are placed in the digester and covered with sulphite liquor containing free sulphur dioxide. The sealed digester is then brought up to temperature by passing steam thereinto. As the digester heats up, the liquid expands and sulphur dioxide, air, and other gases are released. It is therefore necessary to allow for this expansion in volume by venting the top of the digester and carrying away the mixture of liquid and gases constituting the so-called relief.

A number of schemes have been proposed for an efficient disposition of the relief but none of these has been entirely successful. It has been attempted to recover the sulphur dioxide by subjecting the gaseous component of the relief directly to condensation, but because of the presence of the non-condensables, i. e. air, CO_2 , etc., the recovery of the SO_2 by cooling means ordinarily available is very incomplete. It has also been proposed to recover values in the relief by bringing the relief into contact with a stream of cold acid in an injector device, the velocity of the stream of acid being sufficient to inject the entire quantity of relief into an accumulator. This, however, is subject to the drawback that the non-condensable gases are carried along and are thereby introduced into the accumulator. The presence of such non-condensables in the relief accumulator is a distinct disadvantage because they collect above the acid, thereby diluting the sulphur dioxide in the vapor space and reducing the effective pressure for holding

the sulphur dioxide in the acid. It is then necessary to have a relatively low sulphur dioxide concentration or low temperature, or both, in the acid stored.

I have now discovered that greatly improved results are to be had by subjecting the gaseous component of the relief (the relief being separated into a liquid component and a gaseous component as heretofore proposed) to absorption preferably by cold raw acid liquor under pressure, thereby capturing the SO_2 while permitting the non-condensables, such as air, CO_2 , etc., to be vented from the system, after which all or a portion of the SO_2 absorbed by the liquor may be liberated by heating and liquefied by simple condensation. Preferably, both the liquid component of the relief and the SO_2 charged acid liquor are passed to an accumulator from which the SO_2 may be liberated and condensed as just stated. The SO_2 so condensed is then led to the SO_2 accumulator to be made available for treatment of the charge in the same or the next cook.

Such a system has very distinct advantages, among which may be mentioned:

(1) Practically complete recovery of the sulphur dioxide and heat results while at the same time the non-condensable gases are vented from the system. It will be noted that since the bulk of the heat in the relief is held by the liquid and since there is no reduction of pressure in the absorber system, the absorber acid is warmed comparatively little whereby its absorption efficiency is maintained at a high level. In prior recovery systems, a large amount of relatively strong SO_2 is vented to the raw acid system at low pressure under conditions resulting in a low efficiency of recovery.

(2) It will be further noted that the recovery of the pure sulphur dioxide is entirely independent of conditions in the accumulator and that therefore the temperature of the latter may be maintained at any desired value. If the acid charged to the accumulator is not sufficiently fortified with sulphur dioxide, then it may be supercharged with SO_2 from the SO_2 accumulator. If because of the conditions of the system, the acid in the accumulator is saturated with the sulphur dioxide, any further accumulation of SO_2 carried in by the absorption liquor above saturation is given off and caught in the condenser communicating with the SO_2 accumulator. Due to the absence of the non-condensable gases, the amount of SO_2 held by the accumulator acid is strictly a function of the temperature and the pressure prevailing therein. Since it is com-

paratively easy to keep these values constant, the SO₂ content of the acid is therefore uniform thereby promoting uniform conditions as to the SO₂ content when the accumulator acid is used in the next cook.

(3) Because of the ease of eliminating from the system the non-condensable gases and of the circulation of SO₂ through the system, my improved system readily lends itself to a method of cooking heretofore proposed wherein the chips are first exhausted of their contained air preferably by the action of a stream of sulphur dioxide passed through the chips before charging with acid. This elimination of air increases the rate of penetration of the cooking acid and thus reduces the tendency of the chips to burn at high heating rates.

(4) A further and highly important advantage is that the improved method lends itself to a novel method of cooking in which the liquor charged on the chips carries sufficient heat to bring the whole mass to cooking temperature without the further addition of steam to the digester but with addition of SO₂ as needed. Preferably the chips are previously heated with steam and the air displaced either by steam or SO₂.

Other advantages will be apparent as the description proceeds and the features of novelty will be pointed out in the claims. For the best understanding of the invention, reference may now be had to the following detailed description taken with the annexed drawing showing diagrammatically an illustrative embodiment.

35 As shown, a digester 10 is provided with the usual steam admission pipe 11, blow pipe 12 and relief pipe 13 (which pipe may also receive relief from other digesters not shown), the digester being also provided with a constant pressure relief valve 15 of known construction connected with the digester by means of a pipe 16. Relief pipe 13 communicates with a trap 18 which acts to separate the relief into a liquid portion which passes downwardly through a pipe 19 to an accumulator 20, and a gaseous portion which passes upwardly through a pipe 22 to an absorber 23. The absorber 23, which desirably is of the plate type, has a feed pipe 24 for the absorption menstruum under pressure and a relief pipe 25 which has an automatic valve 26 by means of which the column 23 is vented of the non-condensable gases. The SO₂ enriched liquor travels downwardly from the column 23 to a pipe 28 having preferably a U bend acting as a liquid seal to the top of accumulator 20.

To take care of SO₂ and steam released from the accumulator 20, there is provided a pipe 31 leading to an absorber 33, pipe 34 leading from the top of same to a condenser 35 having a cooling coil 36 and a reflux return pipe 37 which has a U bend. The function of the absorber-condenser unit 33-35 is to condense mostly water vapor in the absorber 33 by action of the reflux from condenser 35 and to condense the SO₂ in column 33. The water condensed in column 33 is returned to the accumulator by means of the pipe 38 also having a U bend. Pipe 40 conveys the liquid SO₂ to trap 41 where any vapors or non-condensable gases are separated and pass upwardly through pipe 42 to absorber 23, said pipe also acting as a pressure equalizer for the system. The liquid SO₂ passes downwardly from trap 41 through pipe 43 to the SO₂ accumulator 44. The liquid SO₂ is withdrawn from accumulator 44 as required through pipe

46, pump 47 (which latter may be a metering device) and pipe 48 by means of which it may be passed either to digester 10 or some other digester in the series not shown, it being understood that a battery of several digesters will be operated with 5 a single accumulator 20.

The operation of my improved system in carrying out a cook with steam and SO₂ may be as follows: Chips are charged into the digester 10 and after putting on the cover acid is pumped 10 into the digester from the accumulator 20 by means of pump 52 and pipe 53. If desired, the acid may be pumped through the charge and back to the accumulator through pipe 19 for a period of time. After the digester is charged 15 with liquor, it may be fortified with sulphur dioxide by pumping the liquid sulphur dioxide into the bottom of the digester from accumulator 44 by means of pump or metering device 47. After sufficient sulphur dioxide is injected, steam 20 is introduced into the digester through pipe 11 until the desired temperature is reached or according to any other schedule. The pressure in digester 10 is regulated by valve 15 which is set to hold the pressure constant within a safe limit 25 of the vessel. As the pressure in the digester increases the valve 15 opens to let out the so-called relief. The latter is separated in the trap 18 into a liquid component which passes to the accumulator 20 by pipe 19 as previously described 30 while the gas passes to absorber 23 by means of pipe 22, the pressure on the accumulator and liquid sulphur dioxide storage being regulated by the control vent valve 26. The menstruum entering pipe 24 under pressure, which is desirably 35 the cold raw treating liquor, becomes laden with sulphur dioxide and then passes through the trapped pipe 28 to the accumulator 20. If the temperature of the mixture in the accumulator is 40 high enough, a mixture of sulphur dioxide and water vapor is evolved and these are conveyed to the fractionating column 33 where the water is removed and returned preferably to the accumulator by pipe 38 as previously mentioned. 45 The sulphur dioxide is condensed in the condenser 35 and conveyed to SO₂ accumulator 44, a small amount being used as reflux through pipe 37. Any uncondensed gas is conveyed through pipe 42 to absorber 23 where it is mixed with the 50 vapors arising from the relief.

The composition of the liquor fed to the absorber will naturally be that which it is desired to use in the subsequent cook, i. e. calcium, magnesium, ammonium, or sodium sulphite, or mixtures of these, together with some dissolved SO₂ but not enough to prevent the liquor from acting as an absorbent for the SO₂ in the relief. It is not necessary that the liquor be acid to start with although if it is alkaline it will pick 60 up CO₂ from the gases which is not desirable. The pressure should be about that of the digester, a typical value of which is around 60 to 75 lbs. gauge so that the pressure within the accumulator may be just slightly under that of the 65 digester.

As previously stated, the cooking operation may be carried out in what I believe to be a novel manner by first charging the digester with chips, removing the air therefrom as by evacuation or by displacement with sulphur dioxide or steam or both, after which the chips are warmed to say 80-90 degrees C. with open steam, then the liquor from the accumulator 20, say at 140 degrees C., is applied thereby bringing up the 75

digester contents to around 120 degrees C. because of the large ratio of liquor to chips used. Then having the digester at the desired temperature, sulphur dioxide is circulated through the digester 5 until the cook is complete, after which the digester can be blown. Desirably, the sulphur dioxide in the blow liquor will be recovered by known means.

Various changes may be made in the process 10 and apparatus without departing from the spirit of the invention. In the claims, by acid liquor I mean liquor containing soluble sulphites suitable for digestion of wood whether such liquor be actually acid or not.

15 I claim:

1. In a sulphite digesting system, the method of recovering digester relief, which consists in first separating said relief into a liquid and a gaseous component but without substantial cooling of said relief, separating the SO₂ from the non-condensibles in said gaseous component by subjecting said gaseous component to the absorptive action under pressure of a non-alkaline menstruum of a nature as to constitute a component of the cooking liquor for the same or subsequent cooks, thereby dissolving said SO₂ to the substantial exclusion of the non-condensibles, venting the latter from the system, conducting the SO₂-enriched menstruum to an acid accumulator, likewise under pressure, continuing the admission of said menstruum to said accumulator while maintaining the temperature of the latter sufficiently high to release an excess of SO₂ gas, withdrawing said excess SO₂ from said accumulator, and subjecting the SO₂ to cooling to liquefy same.

2. The method according to claim 1 in which said accumulator is maintained in equilibrium with said gaseous component undergoing absorption and said excess SO₂ gas undergoing cooling to liquefaction.

3. In a sulphite digesting system, the method of recovering digester relief, which consists in first separating said relief into a liquid and a gaseous component but without substantial cooling of said relief, separating the SO₂ from the non-condensibles in said gaseous component by subjecting said gaseous component to the absorptive action under pressure of a non-alkaline menstruum of a nature as to constitute a component of the cooking liquor for the same or subsequent cooks, said menstruum being fed in counter current relationship to said gaseous component, thereby dissolving said SO₂ to the substantial exclusion of the non-condensibles, venting the latter from the system, conducting the SO₂-enriched menstruum to an acid accumulator, likewise under pressure, continuing the admission of said menstruum to said accumulator

while maintaining the temperature of the latter sufficiently high to release an excess of SO₂ gas, withdrawing said excess SO₂ from said accumulator, separating said SO₂ from attendant water vapor by rectification, and subjecting the SO₂ to 5 cooling to liquefy same.

4. In a sulphite digesting system, the method of recovering digester relief, which consists in first separating said relief into a liquid and a gaseous component but without substantial cooling of said relief, separating the SO₂ from the non-condensibles in said gaseous component by subjecting said gaseous component to the absorptive action under pressure of a non-alkaline menstruum of a nature as to constitute a component of the cooking liquor for the same or subsequent cooks, thereby dissolving said SO₂ to the substantial exclusion of the non-condensibles, venting the latter from the system, conducting the SO₂-enriched menstruum to an acid accumulator, likewise under pressure, continuing the admission of said menstruum to said accumulator while maintaining the temperature of the latter sufficiently high to release an excess of SO₂ gas, withdrawing said excess SO₂ from said accumulator, separating said SO₂ from attendant water vapor by rectification, and subjecting the SO₂ to 10 cooling to liquefy same, 15 while venting non-condensibles at this point.

5. The method according to claim 1, including 20 the step of adding the liquid component of the relief to said accumulator.

6. The method according to claim 1 in which the pressures employed in the SO₂ absorption step and in the acid accumulator are approximately 25 that of the digester.

7. In a sulphite digesting system, the method of recovering digester relief, which consists in first separating said relief into a liquid and a gaseous component but without substantial cooling 30 of said relief, separating the SO₂ from the non-condensibles in said gaseous component by subjecting said gaseous component to the absorptive action under pressure of a non-alkaline menstruum of a nature as to constitute a component 35 of the cooking liquor for the same or subsequent cooks, thereby dissolving said SO₂ to the substantial exclusion of the non-condensibles, venting the latter from the system, conducting the SO₂-enriched menstruum to an acid accumulator, likewise under pressure, continuing the admission 40 of said menstruum to said accumulator while maintaining the temperature of the latter sufficiently high to release an excess of SO₂ gas, withdrawing said excess SO₂ from said accumulator, and subjecting the SO₂ to cooling to liquefy 45 same and passing liquefied SO₂ so obtained back to the digester.

EDWARD M. FRANKEL.
